UNITED STATES PATENT OFFICE

122,043

DESIGN FOR AN ASH TRAY

Walter J. Clay and Hubert S. Bell, Houston, Tex.

Application November 6, 1939, Serial No. 88,070

Term of patent 3½ years

To all whom it may concern:

Be it known that we, Walter J. Clay and Hubert S. Bell, citizens of the United States, residing at Houston, Harris County, Texas, have invented a new, original, and ornamental Design for Ash Trays, of which the following is a specification, reference being had to the accompanying drawing, forming part thereof.

Fig. 1 is a top plan view of the ash tray showing our new design, and

Fig. 2 is a central vertical section through the device.

We claim:

The ornamental design for an ash tray, as shown.

WALTER J. CLAY.
HUBERT S. BELL.
